No. 36,306.

Patented May 5, 1903.

UNITED STATES PATENT OFFICE.

CHARLES J. AHRENFELDT, OF NEW YORK, N. Y.

DESIGN FOR A TEAPOT OR SIMILAR ARTICLE.

SPECIFICATION forming part of Design No. 36,306, dated May 5, 1903.

Application filed February 7, 1902. Serial No. 93,090. Term of patent 7 years.

To all whom it may concern:

Be it known that I, CHARLES J. AHRENFELDT, a citizen of the United States, residing at the city of New York, county of New York, and State of New York, have invented and produced a new, original, and ornamental Design for a Teapot or Similar Article, of which the following is a specification, reference being had to the accompanying drawings, forming a part thereof.

In the said drawings, Figure 1 is a side view of a teapot, showing my design. Fig. 2 is an end view of the same.

The body A is of substantially flattened spherical form, having a slightly-flared base E and rim at the top, within which rests the rounded cover B, having a handle C, made to simulate a bud. The spout D is provided with a band from which project leafed ornaments toward the body and fluting toward

the outer end thereof. The handle F is fluted and connected to the body by portions having leafed ornamentation and has a band at its upper part from which project leafed ornaments.

25

What I claim is—

The ornamental design for a teapot or similar article embodying the flattened spherical body A, slightly-flared base and rim thereof, budded handle C, fluted spout D and handle F, substantially as herein shown and described.

30

Signed at the city of New York, in the county of New York, this 29th day of January, 1902.

CHARLES J. AHRENFELDT.
